UNITED STATES PATENT OFFICE

GEORGE H. MAY, OF NEWBURGH, NEW YORK, AND WILLIAM M. GROSVENOR, OF
GRANTWOOD, NEW JERSEY.

PROCESS OF DRYING.

1,075,586.

Specification of Letters Patent. Patented Oct. 14, 1913.

Application filed August 17, 1909. Serial No. 513,253.

To all whom it may concern:

Be it known that we, GEORGE H. MAY and WILLIAM M. GROSVENOR, citizens of the United States, and residents, respectively, of Newburgh, Orange county, New York, and Grantwood, Bergen county, New Jersey, have invented a certain new and useful Improved Process of Drying; of which the following is a specification.

10 The invention relates to an improved process of preparing and drying materials which are coated with water-proofing or other substances applied in the form of a solution, such, for example, as waterproof paper or similar material.

15 The objects of the invention are to dry the material in a uniform and efficient manner, and in such a way as to produce upon the material a smooth and uniform and homogeneous coating which will be tough and durable and continuous, and free from cracks or holes or other imperfections; also to prevent a too rapid drying of the applied coating, as a result of which the quality and durability of the coating will be improved; also to recover the solvent employed in the preparation of the coating so that this solvent may be used over and over again for the same purpose; and generally to provide a method of drying which will be economical and, at the same time, produce a superior quality of finished material.

20 The invention consists, first, in the process of preparing and drying materials coated with substances in solution by first drying the material, then coating it with the substance in solution, then subjecting the coated material to a current of air or other suitable drying medium in a closed chamber, then causing the drying medium to flow through a closed condensing chamber, and then back into the drying chamber, condensing the solvent in the condensing chamber, and drawing off the condensed solvent therefrom, and re-heating the drying medium before it again comes into contact with the material, to the desired temperature.

25 The invention also consists in cooling the drying medium in the condensing chamber to such a point as to condense a part only of the solvent so that the drying medium when it flows from the condensing chamber is partly saturated with the solvent, and in then re-heating this partly saturated drying medium before it again comes into con-

tact with the material, to a temperature a little below the boiling point.

30 The invention also consists in moving the material through the drying chamber at a suitable rate of speed relatively to the character of the coating and of the material to produce a thorough drying of the same before it passes out of the drying chamber.

35 The invention also consists in electrically grounding the parts of the mechanism with which the material comes into moving contact.

40 The invention also consists in applying successive coats to the material while it moves in reverse directions through the drying chamber so as to spread the successive coatings in alternately opposite directions as a result of which imperfections in the goods are covered up.

45 The invention also consists of other steps and features hereinafter described and claimed.

50 In the accompanying drawings an apparatus is shown which is particularly adapted for carrying out this improved process, although other forms of apparatus may be employed for this purpose.

55 In these drawings, Figure 1 is a vertical longitudinal view of the apparatus showing both ends thereof, the middle portion being broken away; and Fig. 2 is a vertical cross-sectional view through the middle of the apparatus.

60 Similar numbers indicate corresponding parts in the two figures.

65 Referring to the drawings, 1 is a closed drying chamber which may be made of any suitable form and size. It is provided with walls 2, 2 of any suitable material. These walls are constructed so as to be substantially impervious to the gases developed in the apparatus, and so as not to be affected by the temperatures employed therein and so as to be substantially fireproof. These walls are preferably provided with a metal lining 3 made of suitable material. This material should be of such a nature as not to be acted upon by the vapors or gases which are produced in the apparatus.

70 4 is an upper wall or covering made of thin cloth or webbing which can be easily torn so as not to confine the gases in case of such explosions as may occur with the mixture of gases present in the apparatus.

75, 5 are bearing surfaces made of metal,

preferably of copper plate, upon which or over which the material moves. These bearing surfaces are supported in any suitable manner, as illustrated in the drawings.

- 5 They are grounded electrically by electrical conductors arranged in any suitable manner. For example, 6 is a wire connecting the bearing piece 5 with the metal lining 3 of the drying chamber, and 7 is a 10 wire connecting the metal lining with the heating pipes 8 placed at the lower part of the drying chamber, or in any other suitable location. 9, 9 are baffle plates extending throughout the length of this drying chamber 15 and projecting from the sides of the chamber toward the middle thereof in the manner clearly shown in Fig. 2. These baffle plates cause the ascending current of air to pass to the middle of the chamber and then underneath the material to the edges thereof, and then across the top of the material to the middle thereof, and then upwardly to the top of the drying chamber.

10 represents the material which is being dried.

11 is the condensing chamber which is separated from the drying chamber by the wall 12, and which is connected with the drying chamber at the top and bottom, as 30 clearly shown in Fig. 2, to permit of a continued circulation of the drying medium up through the drying chamber, then into the top of the condensing chamber, and then down through the condensing chamber, and 35 then into the bottom of the drying chamber where it is re-heated. The condensing chamber is provided with a condensing coil 13 through which cold water, or other refrigerating fluid, may be passed so as to 40 maintain a suitable temperature in the condensing chamber.

14 is a trough or receptacle to receive or catch the condensed solvent, or solvent and water, which is condensed out of the drying medium. The coil 13 is extended down to the lowest point of the trough 14 so as to further cool the solvent after it has been condensed to avoid re-evaporation.

15 is a discharge pipe leading from the 50 receptacle 14 through which the liquid or solvent can be drawn off or removed from the condensing chamber so that it can be again used in preparing the coating substance which is applied to the material to 55 be dried.

16 is a by-pass in the condensing chamber to permit the drying medium to escape past receptacle 14.

17 is a hinged door forming one side of 60 the condensing chamber, by means of which ready access can be had to the condensing chamber and the condensing pipes.

18 is the supply pipe of the heating coil, and 19 is the return pipe of the same.

65 20 is a chamber for inclosing the coating

device. The walls of this chamber are made substantially tight so as to prevent, so far as possible, the vapor or solvent in the drying chamber from escaping from the apparatus.

21, 21 are movable hinged covers in the upper wall of the chamber 20, preferably provided with panes of glass through which the operation of the coating and spreading devices can be easily observed, and by 75 means of which ready access can be had to these devices.

22 is a spreading device or knife adapted to slide up and down in bearings in the side walls of the chamber 20 as shown. 80 This knife is preferably made of metal, and suitably grounded by connecting it electrically with the metal frame of the machine as by the wire 23. Any other suitable form of coating or spreading device may be used. 85

24, 24 are rolls for supporting the material on either side of the coating device. They are also preferably grounded electrically as by the contact brushes 25 which may be connected in any suitable manner 90 with the metal lining of the apparatus.

26, 26 are pieces made of some spring material between which the material to be dried passes into the chamber 20. These spring pieces form a tight joint at the place 95 where the material passes into the chamber 20 and so prevent any substantial leakage of vapor or solvent from the apparatus. If the pieces 26 are made of metal they should be suitably grounded.

100 The coating composition is held in any suitable reservoir such as the tank 27, which is connected by a pipe 28 with a funnel 29 extending through an opening in the hinged cover 21 at a point outside of the knife 22. The pipe 28 is provided with a valve 30, and in this manner the coating composition can be fed at any rate desired into the chamber 20 on to the material in front of the spreading or coating device.

110 In Fig. 1, 31 represents a quantity of coating composition which has been fed on to the material. The chamber 20 is provided with a recess or depression formed by the wall of the chamber and adapted to receive 115 the drip tank 33 which is placed immediately below the coating device so as to receive or catch any surplus of the coating composition which may drop down from the material. When the tank 33 is full it can 120 be withdrawn and emptied in any suitable manner. Each end of the machine is provided with a chamber 20 such as already described, with all the parts from 21 to 33 inclusive. The opening for the admission 125 of the material in the chamber 20 at one end of the machine, is on the same level as the opening for the discharge or admission of the material in the chamber 20 at the other end of the machine. Each end of the 130

device is also provided with suitable driving, holding and tension devices. Any suitable devices may be employed for this purpose. In the form of apparatus illustrated, 5 34 is a roller which acts as a receiving roller when its end of the machine is used as the discharge end, and as the supply roller when its end of the machine is used as the supply end. This roller is slipped onto a 10 square shaft 35 mounted in suitable bearings in the frame of the machine. 36 is a driving roller or drum, and 37 is an intermediate roller. The driving roller may be driven by any suitable means. The particular form 15 of these driving, holding and tension devices forms no part of the present invention, as any suitable apparatus may be employed for this purpose.

No claim is made in this present apparatus 20 for the machine illustrated in the drawings, as this machine is described and claimed in the co-pending application of George H. May and William M. Grosvenor, Serial No. 485,401, filed on March 24, 1909.

25 The machine is so constructed that the material may be passed through the machine in one direction, being coated with composition as it passes through the chamber 20, and being dried on its way through the drying chamber, and it may then be passed back 30 through the machine in the opposite direction for an additional coating to be applied to the material, or it may only be subjected, upon being returned through the machine, 35 to further drying if it is necessary.

The improved method is carried out in this apparatus in the following manner, assuming that the coating substance to be applied to the material is made of ceresin 40 dissolved in benzol: The coating solution is placed in the tank 27 and is fed through the pipe 28 onto the top of the material in front of the coating or spreading knife 22, as illustrated at the left hand end of Fig. 1. 45 The material 10 is passed through the apparatus from left to right, as shown in this figure, and the coating composition is spread evenly and uniformly over the upper surface of the same by the device 22. The material thus coated is passed through the drying chamber 1 at such speed as may be suitable, relatively to the thickness and character of the coating. The air in the 50 drying chamber is heated by the heating coil 8 to a temperature of about 140° Fahrenheit. The heated air rises by operation of gravity through the chamber 1 and is deflected by the baffle plates 9 and brought into contact with the material to be dried 55 throughout the length of the drying chamber, and thus heats the material and causes the evaporation of the benzol contained in the coating composition, and also of any water that there may be in the material, or 60 of a substantial part of the benzol and

water. The drying medium then flows into the upper part of the closed condensing chamber 11, and is brought into contact with the cooling coils 13, and is thereby cooled, and as a result of this substantially all of 70 the water is condensed out of the air, and a considerable portion of the solvent is also condensed.

The temperature of the condensing chamber is maintained at about 110 degrees Fahrenheit. The result of this is that only a part of the benzol is condensed, while substantially all of the water is condensed. The condensed benzol and water flow down into the receptacle 14 where they are further 80 cooled to prevent evaporation and are drawn off through the pipe 15, and are thus recovered, and the benzol may be again used for preparing the coating composition. The drying medium flows away from the condensing coils through the by-pass 16 into the lower part of the condensing chamber, and then flows back into the lower end of the drawing chamber underneath the heating coils. When the drying medium passes 90 away from the condensing coils 13 it is substantially free from water, but is partly saturated with the benzol. By thus regulating the amount or portion of the solvent which is condensed, it is possible to avoid 95 the formation or use of highly explosive mixtures, thereby securing additional safety and economy. The drying medium passes upwardly through the drying chamber, and is re-heated by contact with the heating 100 coils 8 to a temperature of about 140 degrees Fahrenheit. It is then brought into contact again with the material 10 and causes a further evaporation and removal of solvent and water from the said material. By 105 reason of the fact that the drying medium when it is brought into contact with the material is partially saturated with solvent, the evolution or evaporation of the solvent from the material is less drastic and abrupt, and 110 the drying is more uniform. As a result of this the film or layer of coating substance is less likely to be ruptured, and the coating itself, when finally dried, is more uniform in character and of a smoother surface, 115 and with many substances is also less brittle. The drying medium then flows to the upper part of the condensing chamber and down through the condensing chamber as before, as a result of which substantially all 120 the water which it carries is condensed and a part of the solvent, as already explained. This operation is carried on continuously, the material being moved through the drying chamber at such a rate of speed that it 125 will be thoroughly dried before it leaves the discharge end of the apparatus, and receiving other coats as required by reverse passage through the apparatus; or the material may be partly dried in its first passage 130

through the apparatus, and may be passed back through the same as many times as may be necessary to thoroughly complete the drying operation. The drying chamber, 5 and the two connected chambers 20, 20 and the condensing chamber, are all closed so as to form a closed circuit, and they are made as tight as possible so as to prevent any escape or leakage of the solvent-bearing 10 vapors. When successive coats are applied to the material it will be observed that the second coat is applied to, or spread upon, the material in a direction the reverse of that in which the preceding coat was applied to or spread upon the material; and this is done without disconnecting the material from its actuating mechanism. As a 15 result of this, any imperfections which may occur in the first coat are filled up or covered 20 up by the application of the second coat.

As a result of employing the upper wall 4 made of thin cloth or webbing as described above, the drying medium can be circulated at atmospheric pressure by the action of 25 gravity free from the influence of the outside pressure or from outside disturbances of any nature, and yet provision is made for the escape of a portion of the drying medium in case of any substantial increase 30 of internal pressure caused, for example, by an explosion. The action of the drying medium is made independent of the conditions existing outside of the apparatus, as the outside atmosphere has no access to the 35 apparatus, but, at the same time, should any explosion occur, a vent is provided for the gases formed thereby, as a result of which the apparatus would not be injured, or the injury would be reduced to a minimum. 40

When the complete invention is employed the material is dried by any suitable means before it is introduced into the apparatus, so that any moisture or water contained 45 therein will be substantially eliminated before the coating substance is applied to the material. As a result of this the amount of water which is evaporated in the apparatus and condensed in the condenser, is reduced 50 to a minimum, and the liquid drawn off from the condenser contains a smaller proportion of water.

It will be apparent that other coating substances may be used in place of ceresin, 55 and that other organic solvents may be employed instead of benzol and solvents such as carbon tetrachlorid (CCl_4) are regarded as organic solvents. Also that when in this specification "substance in solution" is used, 60 it is not intended that all of the substance must be in solution,—only sufficient of it

need be dissolved to soften the substance and render it more or less plastic.

The invention secures marked advantages, some of which are as follows: The material 65 is dried by a medium already partly saturated with the solvent, which makes the drying less rapid or abrupt, and produces a better quality of coating and a more durable one. The solvent, which is generally 70 expensive, is almost entirely recovered and saved so that it may be used over and over again, thus producing very substantial economy in the operation. The fact that the drying medium is moist with solvent 75 when it enters the drying chamber and comes into contact with the heating coils, enables it to transmit heat to the fabric more quickly than if the medium were perfectly dry. The specific heat of the moist me- 80 dium is greater than the specific heat of the medium when dry. The drying is also accomplished with a minimum expenditure of heat, as excessive temperatures in the drying chamber are purposely avoided. The 85 drying medium may be maintained in a practically non-explosive mixture; the possibility of ignition is further reduced by avoiding stray electrical discharges; and, finally, should ignition occur, an unrestrained and therefore harmless explosion is 90 permitted.

The method is simple and easily carried on.

What is claimed as new, is as follows: 95

The improved method of drying coated sheets and the like carrying volatile organic solvents, which consists in causing the sheet to move through a drying medium during the drying operation, simultaneously causing the drying medium to circulate about the sheets, the drying medium being partially saturated with the organic solvent vapors to be removed before it comes into contact with the sheet, and heated to a temperature below the boiling point of the solvent, the temperature and saturation being so adjusted relatively to one another so that premature surface drying of the coating is prevented, and whereby the movement of the 100 medium causes the body of the sheet and coating to become gradually heated and the vapors to be driven off gradually to prevent blistering, bubbles and pinholes.

In testimony whereof, we have signed our 115 names to this specification, in the presence of two subscribing witnesses.

GEORGE H. MAY.

WILLIAM M. GROSVENOR.

It is hereby certified that in Letters Patent No. 1,075,586, granted October 14, 1913, upon the application of George H. May, of Newburgh, New York, and William M. Grosvenor, of Grantwood, New Jersey, for an improvement in "Processes of Drying," an error appears in the printed specification requiring correction as follows: Page 3, line 89, for the word "drawing" read *drying*; and that the said Letters Patent should be read with this correction therein that the same may conform to the record of the case in the Patent Office.

Signed and sealed this 9th day of December, A. D., 1913.
